UNITED STATES PATENT OFFICE.

SIMON, KLEIN, OF NEW YORK, N. Y.

SAFETY-RAZOR-SHARPENING DEVICE.

1,160,178.

Specification of Letters Patent. Patented Nov. 16, 1915.

Application filed October 16, 1913. Serial No. 795,438.

To all whom it may concern:

Be it known that I, SIMON KLEIN, a citizen of the United States, and a resident of the borough of Manhattan, city, county, and State of New York, have invented certain new and useful Improvements in Safety-Razor-Sharpening Devices, of which the following is a description in such full, clear, and exact terms as will enable any person skilled in the art to which it pertains to make and use the same.

My invention relates to that class of safety razor sharpening devices in which the passage of the strop between the rollers in the frame operates to rock the razor holder back and forth so that the razor will be properly sharpened.

My invention resides in certain novel features of construction in said safety razor sharpening devices all of which will be fully pointed out and described hereinafter.

Reference is now had to the accompanying drawing which represents as an example the preferred embodiment of my invention and in which drawing—

Figure 1 is a front elevation of the device embodying my improvements; Fig. 2 is a side elevation of the same; Fig. 3 is a cross-section on the line 3—3 of Fig. 1 and Fig. 4 is a perspective view of the combination holder, rock-bar and gearing.

Referring to Fig. 1, 10 indicates a handle which is screwed or otherwise connected to a frame 11. 12 is a roller which revolves within the frame its ends projecting through the frame and having pinions 13 attached thereto. Below the roller 12 a bar 14 is fitted in slots in the frame 11 and is adapted to be moved up and down said slots. Upon the bar 14 are sleeves 15 which revolve around the bar as an axis. A spring 16 lies flat upon the bottom of the frame 11 its ends being curved up to engage the bar 14 at openings between the sleeves 15 provided for the purpose. The spring 16 presses against the bar 14 and except when pressure is exerted upon the bar 14 in the opposite direction it is held against the upper ends of the slots in which it slides. The pinions 13 engage the gears 17 which are pivoted on pins 18 around which however they can only revolve part way as their perimeters are not complete circumferences but are interrupted by the rock bar 19 which is formed of the same piece of metal as the gears 17. On the top of the rock bar are wings 20, also formed

of the same piece of metal as the gears 17 and rock bar 19, which are bent upward and almost meet. Between the wings 20 is placed a sheet of metal 21 which lies flat against the interior surface of the wings and extends beyond their edges.

When in operation the razor blade is inserted between the ends of the lining sheet 21 as shown in Fig. 3, and as also shown in said figure, the razor strop is passed between the roller 12 and the sleeves 15 a tight engagement being secured because the spring 16 presses upward the bar 14 and this pressure is communicated to the sleeves 15. When the strop is drawn to the right the revolution of the roller 12 is communicated to the pinions 13 which in turn actuate the gears 17 to which the rock bar 19 is attached and as the wings 20 are of a piece with the rock bar the razor is rocked to the right presenting one side to the strop until the end of the strop is reached. The strop is then drawn to the left and the device acts in the opposite direction, the razor being rocked to the left and presenting its other side to the strop until the other end of the strop is reached when same is again drawn to the right. It will be seen that by this means the razor is sharpened on each side to an equal degree.

It is well for me to observe that devices for obtaining these results are very common and that my invention resides in certain special features of construction which are the introduction of the spring 16 to hold the sleeves 15 in tight engagement with the razor strop and the formation of the gears 17, rock bar 19 and wings 20 from the same piece of metal as best shown in Fig. 4.

The advantage of the use of the spring 16 will be apparent because without it the necessity arises of always obtaining a strop of a thickness equivalent to the space between the sleeves 15 and the roller 12. The method of making the gears, rock bar and wings of the same piece of metal while involving no advantage in operating the device is of great importance to the manufacture because the part of the device can in this way be manufactured by two operations, *i. e.*, stamping it out in correct form and then bending up the wings.

Having thus described my invention, what I claim as new and desire to secure by Letters Patent of the United States is:—

1. A blade holder consisting of a single

piece of sheet metal having resilient blade gripping wings projecting therefrom in one direction and integral portions projecting in the opposite direction and having gears formed thereon.

2. A blade holder consisting of a single piece of sheet metal having opposed resilient blade gripping wings projecting in one direction and integral portions projecting in the opposite direction and having segmental gears formed thereon, the last mentioned

portions further having perforations concentric with the gears to receive a journal shaft.

In testimony whereof I have hereunto ¹⁵ signed my name in the presence of two witnesses.

SIMON KLEIN.
